UNITED STATES PATENT OFFICE.

ALBERT H. HEBBARD, OF CLEVELAND, OHIO, ASSIGNOR TO THE CLEVELAND TARGET COMPANY, OF SAME PLACE.

DESIGN FOR A FLYING TARGET.

SPECIFICATION forming part of Design No. 17,089, dated February 8, 1867.

Application filed September 23, 1886. Serial No. 214,384. Term of patent 14 years.

To all whom it may concern:

Be it known that I, ALBERT H. HEBBARD, a citizen of the United States, residing at Cleveland, in the county of Cuyahoga and State of Ohio, have invented and produced a new and original Design for Flying Targets, of which the following is a specification, reference being had to the accompanying drawings, forming part thereof.

10 Figure 1 is a plan, and Fig. 2 is a side elevation, of a flying target embodying my invention.

Flying or so-called "bird" targets are necessarily dish-shaped, and in their flight present substantially an edge view to the marksman. Heretofore these targets have usually been of a single shade, or such as the material gave of which the target was made, and hence could not be readily seen while flying through the air. To overcome this objection I make 20 the outer surface of the target of contrasting shades.

The leading feature of my design consists in

one or more bands on the convex portion of the target, the said bands contrasting in shade 25 with the remaining portions of the target. One broad band, *a*, located on the convex portion of the target, embodies my design, although two or more bands, as at *a* and *b*, Fig. 2, may be employed in the place of the single 30 band.

What I claim is—

In a design for a dish-shaped flying target, the ornamentation of the same, consisting in one or more bands on the convex surface of 35 said target, the said band or bands contrasting in shade with the remaining portion of the target, substantially as set forth.

In testimony whereof I sign this specification, in the presence of two witnesses, this 15th 40 day of July, 1886.

ALBERT H. HEBBARD.
